(57) **CLAIM**

An ornamental design for an automobile shift lever cover, as shown and described.

DESCRIPTION

FIG. 1 is a first perspective view of an automobile shift lever cover;

FIG. 2 is a second perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The dot-dash lines represent boundaries of the claimed design and the broken lines illustrate environmental structure only and form no part of the claimed design.
